UNITED STATES PATENT OFFICE.

FRANCIS T. JOHNSON, OF CHICAGO, ILLINOIS.

DRIER.

Application filed November 27, 1922. Serial No. 603,393.

This invention relates to improvements in driers and heaters, and especially to comparatively small household driers intended for use in drying laundry, although, of course, it might be made in sizes applicable to many purposes. One object is to provide a drier in which the danger of scorching or burning the garments is reduced to a minimum. Another object is to provide a drier 10 in which the supports for the garments are cool. Another object is to provide a drier in which the walls of the drier are heated only indirectly and are therefore prevented from being overheated. Other objects will appear from time to time throughout the specification and claims.

My invention is illustrated more or less diagrammatically in the accompanying drawings, wherein—

20 Figure 1 is a front elevation of the drier with parts broken away and parts in section;

Figure 2 is an enlarged front elevation of a portion of the heating unit with parts in section and parts broken away;

Figure 3 is a vertical cross section taken on line 3—3 of Figure 2;

Figure 4 is a vertical cross section on line 4—4 of Figure 1;

Figure 5 is a vertical cross section on line 5—5 of Figure 1;

Figure 6 is a vertical cross section on an enlarged scale on line 6—6 of Figure 5 showing the rod attaching means.

Figure 7 is a view similar to Figure 6 showing the rod removed from its position and the attaching means loosened.

Like parts are designated by like characters throughout.

40 A is the front wall of the drier. It is provided with any suitable door frames A¹, A¹ and with hinges A², A² on which are supported door members, each comprising a front portion A³ and a rear wall A⁴, so that the doors are of double thickness and provided with an air space between their front and rear faces. The doors are provided with opposed closing surfaces A⁵ and A⁶.

50 A hook member B on the upper side of the door frame is adapted to be engaged by a rod B¹, pivoted at B² on one of the door members and loosely confined by the strap B³.

The back of the drier may be formed by a single sheet of metal C. The sides are preferably double. The outer elements C¹, C²

serve as walls of flues and the inner perforated elements C³, C⁴ respectively allow access of air to the interior of the drier and escape therefrom. The member C¹ is formed to leave the flue open at the bottom and closed at the top, the inlet C⁵ serving as an air inlet. The air may enter from the room as shown. The member C² is formed to close the flue at its bottom. The flue is provided at its top with an opening C⁶ which serves as an outlet for the moist air from the clothes. There are a plurality of outlets C⁷ through the member C⁴, and these may be masked by overhanging eaves D, D, which serve among other purposes that of preventing the closure of the opening by holding the garments out of sealing contact therewith. Through the members C³, C⁴ there are a plurality of inlets C⁸.

75 The members C³, C⁴ are further provided with a plurality of transverse hollow tubes D¹. These tubes may be in communication with the interior of the double end walls as shown at D², D² or they may extend clear 80 through both walls and communicate with the outer air as at D³, D³. In either form cooling air is circulated through the tubes, and thus they do not become hot enough to scorch or injure anything which is placed 85 upon them.

70 The tubes D¹ are slotted at one end as at D⁴ and they are slipped into perforations in the member C⁴. The slot is brought into close proximity with the inner edge of the member C⁴ and the locking bar D⁵ which is adjustably held to the member C⁴ by means of the locking bolts D⁶ and the slots D⁷ in which they lie, the locking bar D⁵ being moved up engage the slots D⁴ as shown in 90 Figure 6, and the bolts being tightened. When it is desired to release the tubes, the nuts are loosened and the locking bar is moved down as shown in Figure 7, and the tubes may then be withdrawn.

100 Adjacent the bottom of the drier are a plurality of strap members E which extend clear across the drier and upon which a wire netting E¹ is supported. This netting E¹ serves to hold the articles within the drier 105 away from the heating element and to prevent any scorching.

In the bottom of the drier and out of contact with its side walls is located a tunnel made up of a hood member F. This member is lined on the inside of its top with a heat resisting lining F¹. It extends from end to 110

end of the drier and communicates with the double end walls by means of perforations F^1 , F^2 at each end. Extending into the inside of this tunnel is a burner G which may 5 be of any suitable form, the details of which form no part of the present invention. Although a gas burner is here shown as the heating element, any other suitable heating element might be used. The burner G is 10 supported upon a plurality of members G^1 in the bottom of the tunnel. It is connected from the outside with a gas connection G^2 and is controlled by means of a valve G^3 . The burner extends preferably at right angles 15 to the longitudinal axis of the tunnel.

The wall of the tunnel is perforated with a generally pear-shaped hole H . The hole permits the insertion of the burner and leaves a sufficient amount of additional space 20 so that a match or other lighting means may be inserted through the hole over the pipe. In the wall of the tunnel is a perforation covered by mica member H^1 . Covering the larger part of the burner is an insulating 25 and ventilating cover I . It extends laterally to form the hoods I^1 , I^2 on either side of the tunnel. Beneath the hood in the wall of the member F are a plurality of openings I^2 by means of which air is drawn from 30 the interior of the drier into the heating tunnel.

At either end of the drier on the inside, is a collar J provided with a flange J^1 which is attached to the inside wall of the drier. 35 The member F is placed in position over the collar J , and thus it is removably held in position within the drier.

K is a hand hole in the outer wall of the 40 casing provided with a movable cover K^1 . The hand hole is provided in order that the hand of the operator may be inserted to light the burner.

I claim:—

1. A drier comprising a casing, means 45 for heating the drier, said means comprising a heating element surrounded by said drier and separated from the interior thereof, and means for introducing relatively cool air from outside the drier to said heating 50 element and for removing heated air from said heating element without permitting it to circulate through the interior of said drier, and means for introducing air from the interior of said drier to said heating 55 element.

2. A drier comprising a casing having a plurality of double walls, a heating element within said drier, an enclosure therefor in free communication with the interior of two 60 of said walls, and including means for preventing the egress of air from said heating element into said drier.

3. A drier comprising a casing having a plurality of double walls, one of said walls 65 open adjacent its bottom to the outside and

another of said walls open adjacent its top to the outside, a heating tunnel and means for causing air to circulate through said heating tunnel and to pass out without escaping into said drier, said means comprising a heating element within said tunnel and connections at each end of said tunnel to one of said double walls. 70

4. A drier comprising a casing, means for supporting articles to be dried therein, said 75 means including a plurality of tubes arranged in a plane inclined downwardly from the front to the rear of the casing, said tubes open to the outer air for cooling said tubes. 80

5. A drier comprising a casing provided with a plurality of double walls, means for introducing air to one of said walls and for withdrawing it from the other, and a plurality of members for supporting articles 85 within said drier to be dried, said members comprising tubes mounted upon the interior of the drier in communication with said double walls whereby the circulation of air through said tubes is permitted. 90

6. A drier comprising a casing provided with a plurality of double walls, means for introducing air to one of said walls and for withdrawing it from the other, and a plurality of means for supporting articles within 95 said drier to be dried, said means comprising tubes mounted upon the interior of said drier in communication with said double walls whereby the circulation of air through said tubes is permitted, a heating element 100 within said casing and separate therefrom, and means for circulating air past said heating element without permitting it to enter the interior of said casing. 105

7. A drier comprising a casing, means for heating said drier, said means comprising a heating element located within said drier, means for circulating air past said heating element and for discharging said air without permitting it to enter said casing. 110

8. A drier comprising a casing, means for supporting articles to be dried therein, comprising a plurality of slotted rods, portions of the walls of said drier being perforated and adapted to receive the ends of said rods, and engaging bars slidably mounted upon the walls of said casing and adapted in locking position to enter the slots in said bars and to hold them against removal. 115

9. A drier comprising a casing, means for supporting articles to be dried therein, comprising a plurality of slotted rods, portions of the walls of said drier being perforated and adapted to receive the ends of said rods, and engaging bars slidably mounted upon the walls of said casing and adapted in locking position to enter the slots in said bars and to hold them against removal, the walls of said casing into which the bars project being double and serving to cause a circula- 120
125
130

tion of air therethrough, said bars being hollow whereby air is permitted to circulate from said double walls through said hollow bars.

5 10. A drier comprising a casing having a plurality of double walls, a heating element within said drier, an enclosure therefor in free communication with the interior of one of said walls, and means for preventing the egress of air from said heating element into said drier.

10 11. A drier comprising a casing, means for supporting articles therein, said means including tubes and means for cooling said tubes including an air conduit for conducting cool air to said tubes.

15 12. A drier comprising a casing, means for supporting articles therein, said means including tubes and means for cooling said

tubes including an air conduit for conducting cool air to said tubes, in combination with a discharge passage into which cool air from said tubes is discharged, there being a current of air passing through said discharge passage.

20 25 13. A drier comprising a casing, means for supporting articles therein, said means including tubes and means for cooling said tubes including an air conduit for conducting cool air to said tubes, in combination with a discharge passage into which cool air from said tubes is discharged, there being a current of heated air passing through said discharge passage.

30 35 Signed at Chicago, county of Cook and State of Illinois, this 17th day of November, 1922.

FRANCIS T. JOHNSON.
